UNITED STATES PATENT OFFICE.

ANTON CYPRA, OF WORCESTER, MASSACHUSETTS

DIVING-HELMET.

1,000,721.

Specification of Letters Patent. Patented Aug. 15, 1911.

Application filed October 26, 1910. Serial No. 589,173.

To all whom it may concern:

Be it known that I, ANTON CYPRA, a citizen of the United States, residing at Worcester, in the county of Worcester and State of Massachusetts, have invented certain new and useful Improvements in Diving-Helmets, of which the following is a specification, reference being had to the accompanying drawings.

10 This invention relates to certain new and useful improvements in diving helmets and has for its object to provide a device of this character which is adapted to be arranged over the head of the diver and is connected to an air supply tank carried upon his back, said tank having means arranged therein for constantly supplying fresh air to the interior of the helmet, said means being under the control of the diver.

15 A further object is to provide a simple device of this character comprising the helmet casing and an air tank, said casing and tank being connected by air tubes, and fans in the casing and electric batteries carried by said casing, switches being arranged in the interior of the helmet under the control of the diver, and a head light arranged on said helmet electrically connected with one of said switches.

20 With these and other objects in view, the invention consists of the novel features of construction and the combination and arrangement of parts hereinafter fully described and claimed, and illustrated in the accompanying drawing, in which—

Figure 1 is a side elevation illustrating the application of the device; Fig. 2 is an enlarged vertical section through the helmet and the air tank; and Fig. 3 is a section taken on the line 3—3 of Fig. 2.

Referring more particularly to the drawings 5 indicates my improved helmet which comprises the regular metallic head casing 6 and the neck piece 7 which is adapted to be suitably fastened to the diver's suit. The casing 6 is provided in its front and sides with the heavy glass lenses 8 through which the diver may obtain a clear and distinct view of his surroundings. I preferentially form the helmet casing at its top with a knife blade 9, the body of which is tubular and is provided in its front with a lens 10 through which the light is emitted from an electric bulb 11 arranged therein. The knife 9 is adapted to be used by the diver

in defending himself against the attacks of the habitués of the sea.

An air tank 12 of ample size is strapped or otherwise secured upon the diver's back, and is connected to the rear of the helmet, by means of the tubes 13 13'. These tubes would preferably be formed integral with the helmet and the tank, though it will, of course, be understood that they can be separately formed if desired and secured thereto, in any suitable manner. The short tube 13 which connects the helmet to the main tube 13 is adapted to return the air from the helmet to the supply tank. The tank 12 is supplied with fresh air before the device is arranged upon the diver, by connecting the tube of an air pump to the end of the pipe 13 where it enters the helmet. The tank 12 is of sufficient capacity to permit the diver to remain below the surface of the water for an extended length of time before a fresh supply of air is necessary. When the air supply becomes exhausted of the oxygen therein, the diver returns to the surface and the vitiated air is exhausted from the tank by operating the fans therein. The fans 14 and 17 cause a continuous circulation of the fresh air between the tank and the helmet, so that the diver can remain below the surface of the water for a greater length of time than would be possible were these fans not provided. Upon the opposite sides of the tank 12 suitable fans are arranged, the fan 14 being electrically connected with the wire 15 by means of a plug 16 which is inserted through the bottom of the air tank and connects the supply wire 15 with the current wire of the fan through the medium of a suitable contact arranged in the tank. The supply wire 15 extends above the surface of the water and is suitably connected with the source of current. The other of the fans 17 is electrically connected to the batteries 18 carried in the bottom of the supply tank. This fan under normal conditions is not in operation and is controlled by means of a switch 19 arranged in the interior of the front of the helmet. The battery wire of the fan 14 is also connected to the switch 20 adjacent to the switch 19. Another switch 21 is also arranged in the helmet and controls the supply of current to the electric light bulb 11 arranged in the top of the helmet casing. These switches 19, 20, and 21 are arranged adjacent to each other and are

adapted to be operated by the diver by using his teeth to turn the same. In this manner he may always obtain an ample supply of fresh air, the air being driven by the fans through the tube 13 into the helmet and returned back to the supply tank through the branch tube 13'. In the event that the wire 15 should become entangled in the debris of a wrecked vessel around which the diver is 10 working, he may readily put the other of the fans 17 in operation by simply turning the switch 19.

From the foregoing it is believed that the construction, operation and many advantages of my improved diver's helmet will be apparent without necessitating a more extended description. The device is simple, light and of great convenience and efficiency in use. The necessity of pumping air 20 through tubes connected to the diver's helmet is eliminated and he is enabled to remain under the surface of the water for a great length of time without requiring an additional air supply.

25 While I have shown and described the preferable embodiment of my invention, it will be understood that the same is susceptible of many minor modifications without departing from the essential features or sacrificing any of the advantages thereof.

Having thus described the invention what is claimed is:

1. A diver's helmet comprising a casing having a plurality of lenses therein, in combination with an air tank carried by the diver, tubes connecting said tank and helmet, and electrically actuated fans in said tank adapted to supply a constantly circulating current of air to the helmet.

40 2. A diver's helmet comprising a casing having lenses in the sides and front thereof, in combination with an air supply tank carried by the diver, tubes connecting said tank with the helmet, and electrically actuated

fans in said tank and under the control of 45 the diver adapted to supply a constantly circulating current of air to the helmet.

3. A diver's helmet comprising a helmet casing having vision lenses therein, an electric bulb in the top of said casing, in combination with an air supply tank carried by the diver, tubes connecting said tank and helmet, electrically operated fans in said tank, adapted to supply a constantly circulating current of air to the helmet and switches in said helmet adapted to be actuated by the diver to control said fans and the light in said helmet.

4. A diver's helmet comprising a casing having vision lenses in its sides and front, a tubular light casing formed upon the top of the first named casing having a lens in one end, an electric light bulb in said last named casing, said latter casing being formed upon its top with a knife edge, in combination with an air supply tank arranged upon the back of the diver, tubes connecting said tank to the back of the helmet, a plurality of electric batteries in said tank; a fan supported upon opposite sides of the tank, a wire connecting one of said fans with the source of electric supply exteriorly of the tank, connections between the batteries and the other of said fans, connections between said batteries and the electric light bulb in the helmet, and electric switches arranged in the interior of the front of the helmet casing and adapted to be actuated by the diver's teeth to control said light and the fans in said tank whereby a constantly circulating current of air is supplied to said helmet.

In testimony whereof I hereunto affix my signature in the presence of two witnesses.

ANTON CYPRA.
